UNITED STATES PATENT OFFICE.

WILLIAM NEAL MERRITT, OF NOCONA, TEXAS.

CABINET.

No. 797,304.

Specification of Letters Patent.

Patented Aug. 15, 1905.

Application filed March 22, 1905. Serial No. 251,496.

To all whom it may concern:

Be it known that I, WILLIAM NEAL MERRITT, a citizen of the United States, residing at Nocona, in the county of Montague and State of Texas, have invented a new and useful Cabinet, of which the following is a specification.

This invention relates generally to cabinets, and particularly to one adapted for use by post-offices.

The object of the invention is to facilitate the distribution of rural free-delivery mail and to obviate the necessity of looking through a book or a number of pigeonholes to ascertain a temporary change of address or a request to forward mail along with another person's.

With the above and other objects in view, as will appear as the nature of the invention is better understood, the same consists in the novel construction and combination of parts of a cabinet, as will be hereinafter fully described and claimed.

In the accompanying drawings, forming a part of this specification, and in which like characters of reference indicate corresponding parts, there is illustrated one form of embodiment of the invention, capable of carrying the same into practical operation, it being understood that the elements therein exhibited may be varied or changed as to shape, proportion, and exact manner of assemblage, without departing from the spirit thereof.

In the drawings, Figure 1 is a view in elevation of a portion of a cabinet constructed in accordance with the present invention with one of the doors of the pigeonholes shown as open. Fig. 2 is a view in elevation, on an enlarged scale, of one of the compartment-doors. Fig. 3 is a view in vertical transverse section through one of the compartments.

In making the cabinet any number of pigeonholes may be employed, generally seventy-two, and as each is a counterpart of the other a description of one will serve for all.

The cabinet 1 may be constructed of any suitable material, preferably of wood, and is divided by vertical partitions 3 and horizontal partitions 4 into any desired number of pigeonholes 5, each of which is closed by a door 6. Each pigeonhole is divided by a vertical partition 7 into two divisions, one of which is subdivided by horizontal shelves 8 into three compartments, the shelves being preferably constructed of sheet metal and being held in

position by grooves 9, formed, respectively, in the partitions 3 and 7. Each shelf is provided at one end with an upturned flange 10, Fig. 3, and at its other end with a down-turned flange 11, the upturned flange serving to prevent any matter contained within the compartments from being retained when the shelf is drawn out, and the flange 11 serving as a handhold to facilitate operation of the shelf.

Displayed upon each of the partitions 4 is the alphabet, which is divided into groups of three letters, with the exception of "Y" and "Z," and are disposed over each of the pigeonholes. Displayed upon the partitions 3 is the alphabet, which in this instance is shown as divided into groups of four letters arranged adjacent to each pigeonhole. Of course the manner in which the letters are grouped is not essential and may be varied or changed, if found necessary or desirable, as for instance, if there are a fewer number of pigeonholes the number of the letters in each group would be increased, and vice versa.

Upon the outer side of each door is secured in any suitable manner a series of guides 12, which, as shown in Fig. 3, are approximately T-shaped in cross-section and are secured in any suitable manner to a back plate 13, which is attached upon the door. These guides may be of any suitable material, preferably of metal, and are designed to receive strips of paper or pasteboard 14, upon which are displayed directions relative to the distribution of mail-matter, or temporary change of address of a person usually receiving mail at the office employing the cabinet. For the purpose of illustration the upper strip on the door, as shown in Fig. 2, bears the name of "S. W. Dane," and thereafter are fifteen separate initials, these representing the initials of the members of Mr. Dane's household. This slip will also bear a suitable legend indicative of the route carrying the mail, in this instance "Route 3," which indicates that Mr. Dane's mail is delivered by rural free-delivery route 3. Where a change of address is to be observed, slips will be inserted between the guides in alphabetical order. In this instance, as shown in Fig. 2, "Adams" will appear opposite the letter "A" on the partitions 3, and "Banks" opposite the letter "B." As shown in the above figure, the slip bearing the name "Adams" contains the following data: "Adams, Sallie & John, St. Louis, Mo., out 1/10/05." This indicates that the mail of these persons

is to be sent to St. Louis, Missouri, until the 10th day of January, 1905, when the change of address will cease, at which time the slip will be removed. The slip bearing the name of "Banks" will have exhibited thereon the following: "Banks, John, send out with John Acma's mail. R. F. D. No. 5." This means that John Bank's mail is to be sent out along with John Acma's mail, on rural free-delivery route No. 5. Within each pigeonhole there will be a printed blank corresponding to the matter contained in the guides on the outside of the door, and these printed slips will be filled out by the person wishing a change of address and be filed away upon the shelves 8 until the time expires, when the slips will be removed from the shelves and stored in the pigeonhole at the left of the shelves for future reference.

The use of the alphabets displayed upon the partitions 3 and 4 is rapidly to locate a name, to ascertain what disposition is to be made of the mail-matter of a certain person without having to refer to a book or examine the printed slips within the pigeonholes. Thus suppose it be desired to find the name Samuel Jones. The operator would run down the vertical line of letters until the letter "J" is reached, which would be the first letter of the name, and then transversely across the cabinet until the letter "O" appears, which is the first vowel in the name, this being accomplished by running down the horizontally-disposed alphabet, and when "O" is reached there appears the name on the door of the pigeonhole of Samuel Jones.

It will be seen from the foregoing descrip-

tion that by the employment of the cabinet herein described that there will be exhibited in a ready and practical manner all the data relative to the distribution of mail-matter and in such form as to be readily accessible at all times, it being designed that the cabinet will be placed upon a table or other suitable support adjacent to the boxes in which the mail is generally distributed, so that the operator will be enabled at a glance to tell what disposition is to be made of the mail before distributing it.

Having thus described the invention, what is claimed is—

1. A post-office cabinet divided by vertical and horizontal partitions into a plurality of pigeonholes, a door for closing each pigeonhole and provided on its exterior surface with a plurality of guides or holders, the interior of each pigeonhole being divided into two compartments, one of which is subdivided into a plurality of compartments by horizontally-disposed shelves.

2. A post-office cabinet comprising a plurality of pigeonholes each closed by a door having on its exterior, a plurality of guides or holders, each pigeonhole having over it and to one side of it a group of letters to guide the operator in locating a name to determine the disposition to be made of the mail-matter.

In testimony that I claim the foregoing as my own I have hereto affixed my signature in the presence of two witnesses.

WILLIAM NEAL MERRITT.
